UNITED STATES PATENT OFFICE.

JOHANN F. M. PATITZ, OF MILWAUKEE, WISCONSIN, ASSIGNOR TO AELIS-CHALMERS COMPANY, OF MILWAUKEE, WISCONSIN, A CORPORATION OF NEW JERSEY.

SURFACE CONDENSER.

No. 919,308.

Specification of Letters Patent. Patented April 20, 1909.

Application filed December 7, 1906. Serial No. 346,691.

To all whom it may concern:

Be it known that I, JOHANN F. M. PATITZ, a citizen of the United States, residing at Milwaukee, in the county of Milwaukee and State of Wisconsin, have invented certain new and useful Improvements in Surface Condensers, of which the following is a specification.

This invention relates to surface condensers and is intended to increase the efficiency of such condensers by permitting the withdrawal of the water of condensation from superimposed banks of tubes in order that the water which has been condensed by an upper bank of tubes may not be permitted to drop down over the tubes of a lower bank and thereby prevent the steam from coming into close contact with the tubes of said lower bank.

20. A further object of this invention is to so dispose and arrange the several parts of a surface condenser that the maximum cooling effect is produced by the condensing water upon the steam, that the steam may have free access to all tubes through which the cooling water circulates, and that ample steam space shall be provided in the vicinity of the steam inlet.

In the drawings which accompany this specification and form a part thereof and which illustrate an embodiment of this invention and on which the same reference characters designate the same elements in each of the several views,—Figure 1 represents a vertical longitudinal section through a condenser embodying this invention taken on the line *a—a* of Fig. 2. Fig. 2 represents a vertical transverse section taken on the line *b—b* of Fig. 1. Fig. 3 represents a plan view of a section taken on the lines *c—c* of Figs. 1 and 2.

The numeral 1 represents the casing proper of the condenser which may be formed of a casting or plate metal in any convenient or preferable manner, said casing being provided with a steam inlet 2 and the heads 3 and 4, within which heads are secured the condenser tubes 5, said tubes passing through each of said heads so as to afford communication through the condenser from one end to the other thereof.

The numeral 6 represents a casing which is secured to the head 3, and the numeral 7 represents a somewhat similar casing which is secured to the head 4, these casings being

provided to afford a continuous conduit or path for the cooling water; and each of these casings is provided with partitions designated generally by the reference character 8, by which chambers are formed between the heads 3 and 4 of the condenser and the said casings.

One or more entrances for the cooling water may be provided in one of the casings 6 or 7, or preferably, as shown by Fig. 3, two inlets are provided for the condensing water, indicated by the numerals 9 and 10. These inlets communicate with the chambers 11 and 12 respectively, from which chambers the water passes by the tubes of the vertical banks 13 and 14 to the chambers 15 and 16 respectively, whence the water passes by the tubes of the vertical banks 18 and 17 to the chambers 19 and 20 respectively, from which chambers the water passes by the tubes of the vertical banks 21 and 22 to a common chamber 23, from whence it passes by the tubes of the vertical banks 24 and 25 to the common chamber 26 provided with the outlet 27.

The numeral 28 represents feet or supports which may be formed as an integral part of the casting or may be secured thereto in any preferable manner.

The condenser casing 1 is provided with an outlet 29 for the water of condensation and may also be provided with a pipe 30 projected upwardly therein to provide for the separate withdrawal of air from the condenser, which pipe may be placed in communication with a separate dry air pump or may be connected up in any preferred way so that the air will be withdrawn there-through. In the construction of the condenser as shown, the tubes are separated into horizontal banks by partitions 31 which may be formed as an integral part of the condenser casting or which may be plates secured either removably or not within the condenser. In the preferred construction of condenser which is shown by the drawings, these plates extend from a central free space outwardly and downwardly toward the sides of the condenser casing and are provided adjacent said sides with apertures 32 through which the condensed water can fall and drain away to the lower part of the condenser casing.

Near the bottom of the condenser casing is placed a partition 33, which is similar to the partitions just described both in function and

in form, being also provided with the aperture 32; but this partition 33 is extended clear across the condenser, whereby the condenser is in effect divided into two chambers.

5 This partition 33 being upwardly inclined toward the center from each side of the condenser casing, affords a pocket in which air and other uncondensable gases may collect, and the pipe 30 is extended well up to this 10 partition. Pipes 34 for the circulation of the condensing water may be placed below this partition 33 and in proximity to the air pipe 30 for the purpose of cooling the air or other uncondensable gases, thereby increasing the 15 density and diminishing the volume of the fluids to be withdrawn through pipe 30.

In the preferred form of construction, as shown by the drawings, the steam admission pipe is arranged to distribute the steam uniformly with respect to the length of the condenser and some considerable space is left between the banks of tubes at the top of the condenser on the opposite sides of the steam admission inlet, which space is gradually contracted toward the bottom of the condenser, the effect of this arrangement being that the steam while having free access to the interior of the condenser, is easily diverted to each of the several horizontal banks of tubes in parallel layers, so to speak, on each side of the condenser, the arrangement being such that the greatest freedom of movement of the steam is afforded, as the passageways for the steam are not blocked in any way until the steam reaches the condensing tubes.

The operation of the condenser is as follows: Steam being admitted to the condenser through the inlet 2 while the condensing water is passing through the condensing 40 tubes, as previously stated, the steam will flow from the inlet 2 into the central space extending throughout the length of the condenser, and will then flow sidewise over the respective banks of tubes 41, 42, 43, 44, 45, 46, 47, 48, 49 and 50, and being condensed the water will drop onto the plates 31 and 33

to drain by gravity through the apertures 32 to the bottom of the condenser, whence it will escape through the outlet 29, being drawn off by any suitable arrangement of apparatus 50 which will accomplish the purpose, as by an ordinary form of pump. Meanwhile any air or other uncondensable gases which may enter the condenser will collect beneath the partition 33, and being cooled by the condensing 55 water passing through the pipes 34, will be drawn off through the pipe 30.

What I claim is,—

1. The combination in a surface condenser of a casing provided with a steam inlet, tubes 60 arranged in said casing for the passage of the condensing water therethrough, said tubes being so arranged that a large steam space is left adjacent the steam inlet, said space being gradually contracted to the other extremity 65 of the condenser, and means for collecting the water of condensation and removing the same to a common discharge directly from substantially horizontal banks of said tubes.

2. The combination in a surface condenser 70 of a casing provided with a steam inlet, tubes arranged in said casing for the passage of the condensing water therethrough, said tubes being so arranged that a large steam space is left adjacent the steam inlet, said space being 75 gradually contracted to the other extremity of the condenser, and means for dividing the steam leaving said space among separated banks of tubes.

3. The combination in a condenser of 80 banks of horizontal tubes therein for condensing water, a common admission means for distributing steam to all said banks and a means for collecting and commonly discharging water of condensation from all said 85 banks.

In testimony whereof, I affix my signature in the presence of two witnesses.

JOHANN F. M. PATITZ.
